UNITED STATES PATENT OFFICE

152,630

DESIGN FOR A NEEDLE DISPENSER

Patrick T. Marinack, Glendale, and Isaac Preston
Dooley, Burbank, Calif.

Application July 8, 1946, Serial No. 131,364

Term of patent 3½ years

(Cl. D58—12)

To all whom it may concern:

Be it known that we, Patrick T. Marinack and Isaac Preston Dooley, citizens of the United States of America, residing in the city of Glendale and Burbank, respectively, in the county of Los Angeles, State of California, have invented a new, original, and ornamental Design for a Needle Dispenser, of which the following is a specification, reference being had to the accompanying drawings, forming a part thereof.

Fig. 1 is a perspective view of a needle dispenser, showing our new design;

Fig. 2 is a top plan view;

Fig. 3 is a rear elevational view, and

Fig. 4 is an elevational view thereof of the end not visible in Fig. 1.

We claim:

The ornamental design for a needle dispenser, substantially as shown and described.

PATRICK T. MARINACK.
ISAAC PRESTON DOOLEY.
